UNITED STATES PATENT OFFICE.

ARTHUR B. REID, OF CHICAGO, ILLINOIS.

HOOK AND EYE.

No. 853,377.

Specification of Letters Patent.

Patented May 14, 1907.

Application filed September 6, 1900. Serial No. 29,119.

To all whom it may concern:

Be it known that I, ARTHUR B. REID, a citizen of the United States, residing at Chicago, in the county of Cook and State of Illinois, have invented a certain new and useful improvement in Hooks and Eyes, of which the following is a full, clear, concise, and exact description, reference being had to the accompanying drawing, forming a part of this specification.

My invention relates to an improved hook and eye; my object being to provide a novel construction whereby the bill of the hook may be shielded and guarded to prevent the hair and the clothes of the wearer from catching or becoming entangled therein.

It is the object of my invention to provide a hook of that class in which the resilient tongue which protects the bill of the hook 20 may be formed of a single length of wire, the forward end of the tongue being suitably guided as will be hereinafter more particularly described, whereby the lateral displacement of the tongue will be effectually prevented.

In accordance with my invention, I provide the resilient tongue with an intermediate portion adapted to shield and protect the end of the bill and having the forward 30 end suitably guided to limit the lateral movement thereof, and thereby prevent the lateral displacement of the tongue. I preferably arrange the end of the tongue so that the same may be guided between the portions 35 of the wire forming the bill of the hook.

I have illustrated my invention in the accompanying drawing in which:

Figure 1 is a plan view showing the improved hook of my invention and an eye in engagement therewith. Fig. 2 is a view showing the hook and eye in elevation. Fig. 3 is a view showing the eye removed from the hook and showing in dotted lines the position of the resilient tongue when depressed. Fig. 4 is an end view of the hook.

Like letters refer to like parts in the several figures.

The hook is preferably formed of a single piece of wire bent to form a shank having the rear loops a a' and having at its forward end the laterally extending portions or loops a^2 a^3 , and having an intermediate portion of the wire bent to form the bill b of the hook. The particular formation of the fastening devices for securing the hook to the fabric or other material, however, is not essential. The

bill, as illustrated, comprises upright portions of wire b' b' and horizontal portions b^2 b^3 and the point b^3 . The resilient tongue c is bent upward at an intermediate portion 60 to shield and protect the end of the bill and the tongue is adapted to engage the under face of the bill, the upward movement of the tongue being limited thereby, and the end of the tongue is adapted to rest between the 65 parts b' b' of the bill, which act as guides and prevent the lateral displacement of the tongue. I preferably provide at the end of the tongue an upwardly extending portion c' adapted to rest between the portions b' b' 70 of the bill and a rearwardly extending portion c^2 adapted to rest between the portions b^2 b^3 of the bill. By the above construction the lateral displacement of the tongue is effectually prevented by the engagement of 7 the end portion of the tongue with the wires forming the bill of the hook.

When it is desired to place the eye in engagement with the hook the tongue being in its normal position as shown in Fig. 3, the 80 pressure of the eye against the resilient tongue c serves to depress the tongue as shown in dotted lines in Fig. 3, thus permitting the eye to engage the bill of the hook, the resilient tongue serving to yieldingly oppose the disengagement of the eye from the hook. When it is desired, however, to disengage the eye from the hook, pressure exerted upon the eye will depress the tongue thereby permitting the removal of the eye 90 from engagement with the hook.

It will be noted that the tongue is normally located above the shank of the hook and by this arrangement the tongue may be readily depressed in engaging the eye, a decided advantage where the hooks are used on garments which tightly fit the wearer or where the hooks are used in any position in which the shank of the hook rests against a non-resilient surface.

While I have shown the bill and the end of the resilient tongue of particular shape, it will be understood that I do not limit myself to these particular shapes, the essential feature of my invention in this respect being the provision of means for guiding the end of the tongue and preventing the lateral displacement thereof.

Having described my invention what I claim as new and desire to secure by Letters 110 Patent is:—

1. In a hook, the combination with a

shank, having a bill and provided with suitable parts for securing the same to the fabric or other material, of a depressible tongue adapted to engage the bill at an intermediate point and having a part normally resting in front of the tip of the bill to guide extraneous objects over and away from said bill, one end of said tongue being suitably guided to prevent lateral displacement thereof and normally located above said shank.

2. In a hook, the combination with a shank having a bill and provided with suitable parts for securing the same to the fabric or other material, of a depressible tongue having a part normally resting immediately in front of the tip of the bill to guide extraneous objects over and away from said bill, said tongue having the end extended forward and guided by the portions of the hook constituting the bill to prevent the lateral displacement thereof and normally located above the shank of the hook.

3. In a hook, the combination with a shank, having suitable parts for securing the same to the fabric and a bill comprising two upwardly extending parallel portions and a rearwardly extending portion, of a depressible tongue having a part normally resting immediately in front of the tip of the bill to guide extraneous objects over and away from the bill and having the end extended forward to lie between the upright parallel portions constituting the bill to thereby prevent lateral displacement of the tongue, the end of

said tongue being normally located above the shank of the hook.

4. In a hook, the combination with a shank having suitable parts for securing the same to the fabric or other material and a bill, of a depressible tongue having a part normally resting immediately in front of the tip of the bill to guide extraneous objects over and away from the bill and having a portion thereof arranged to lie beneath the eye when the same is in engagement with the bill, said tongue having at its end engaging means for preventing lateral displacement thereof the end portion of said tongue being normally located above the shank of the hook.

5. In a hook, the combination with a shank provided with means for securing the same to the fabric and a bill, of a depressible tongue having a part normally extending in front of the point of the bill to guide extraneous objects away from and over said bill, said tongue being normally located above the shank of the hook and having a portion arranged to engage guiding means to prevent lateral displacement of the tongue.

In witness whereof, I have hereunto subscribed my name in the presence of two witnesses.

ARTHUR B. REID.
